INVENTOR
DAVID ROSEN
BY HIS ATTORNEY
Harry Smith

UNITED STATES PATENT OFFICE.

DAVID ROSEN, OF PHILADELPHIA, PENNSYLVANIA.

COLLAR-BUTTON.

1,283,919.

Specification of Letters Patent.

Patented Nov. 5, 1918.

Application filed May 1, 1918. Serial No. 231,923.

To all whom it may concern:

Be it known that I, DAVID ROSEN, a citizen of the United States, residing in Philadelphia, Pennsylvania, have invented certain Improvements in Collar-Buttons, of which the following is a specification.

My invention relates to that type of collar button which has a head provided with anti-friction means for facilitating passage of the band of a necktie to an fro over the same, the object of my invention being to so construct such a collar button that the presence of the anti-friction device will not interfere with the ready application of the button to or its removal from the buttonhole in the neckband or collar.

This object I attain in the manner herein-after set forth, reference being had to the accompanying drawing, in which—

20 Figure 1 is a top view of a collar button constructed in accordance with my invention;

25 Fig. 2 is a side view of the same partly in section on the line 2—2, Fig. 1;

Fig. 3 is a side view partly in section on the line 3—3, Fig. 1;

30 Fig. 4 is a side view showing the head of the button adjusted for passing through the button hole in the neck band or collar;

Fig. 5 is a view similar to part of Fig. 3 but on a larger scale.

In the drawing, 1 represents the base of the button and 2 the shank projecting from the same. These may be of the usual construction, my invention relating to the head 3 of the button and to the means for mounting the same upon the shank. The head comprises an elongated cup-like structure 4, 40 with pointed ends 5 which are provided with inwardly projecting studs 6 entering openings in the opposite ends of an anti-friction roller 7. This roller 7 is of substantially the same shape as the cup 4 and it is disposed partly within and partly beyond the edge of said cup. The studs 6 serve as pivots on which the roller 7 turns so as to facilitate the free movement over the same of the band of the necktie in effecting proper 45 adjustment of the latter after it has been properly knotted.

The base of the cup 4 is slotted, as shown at 11, in Fig. 5, for the reception of the shank 2 of the button, and said base has, on 55 opposite sides of the slot, segmental pockets 12 for the reception of pins 8 which pro-

ject in opposite directions from the upper end of said shank, as shown in Fig. 2, these pins providing a pivotal mounting for the head 3 of the button so as to permit the 60 same to be turned to a position parallel with the shank, as shown in Fig. 4, in order to render easy the passage of the head of the button through the button hole in the neck band or collar, the pointed forward end 5 of 65 the head readily entering said button hole and the tapering of the head from end to center assuring a gradual spread of the button hole as the head is passed through the same.

In order to normally retain the head of the button in position at right angle to the shank, that portion of the shank 2 between the pivot pins 8 has a squared or shouldered upper face 9, as best shown in Fig. 5, which 75 face bears against a spring plate 10 secured in the bottom of the cup 4, as shown in Fig. 3.

While the bearing of the spring plate 10 upon the shoulders 9, is sufficient to retain 80 the head of the button in its normal relation to the shank and base, as shown in Figs. 1, 2 and 3, it does not prevent the ready turning of the head on the pivot pins 8 to the position shown in Fig. 4 so as to be presented 85 point first to the button hole in the neck band or collar, in applying or removing the button.

The pivoting of the roller 7 upon studs integral with the cup 4 of the button head 90 cheapens and facilitates manufacture by reducing the number of separate parts contained in the button.

I claim:

1. A collar button having an elongated 95 head, a shank upon which said head is pivotally mounted so that it may be swung into line therewith, and an anti-friction roller mounted in said head and having its axis transverse to that of the pivotal mounting 100 of the head.

2. A collar button having, in combination, an elongated head consisting of a cup with inwardly extending studs at its opposite ends, an anti-friction roller extending from 105 end to end of said cup and having end openings for the reception of said studs, and a shank upon which said head is pivotally mounted so as to be swung into line therewith.

3. A collar button having an elongated 110 head with pointed end, a shank upon which

said head is pivotally mounted, and an anti-friction roller rotatably mounted in said head and having its axis transverse to that of the pivotal mounting of the head.

5. A collar button having an elongated head with pointed end, an anti-friction roller rotatably mounted therein and having its axis extending longitudinally of the head, a shank having at its upper end op-

positely projecting pivot studs and an intermediate shouldered portion, bearings in the back of the head for said pivot studs, and a spring plate carried by said head and bearing upon said shouldered portion of the shank. 15

In testimony whereof I have signed my name to this specification.

DAVID ROSEN.
